Archibald C. Brintnall, Denver, Colo.

Application November 8, 1943, Serial No. 509,516

3 Claims. (Cl. 81—78)

This invention relates to improvements in wrenches and has reference more particularly to a wrench of the hook or alligator type.

It is the object of this invention to produce a wrench for general use which shall be of an exceedingly simple construction and which can therefore be manufactured and sold at a comparatively low cost and price.

It is a further object of this invention to produce a wrench which can be employed either with round pipes and bolts or with nuts, either square or hexagonal.

It is a further object of this invention to produce a wrench having an auxiliary gripping jaw or member that can be moved into clamping position during the operation of the wrench and which serves to facilitate the operation thereof.

The above and any other objects that may become apparent as this description proceeds are attained by means of a construction and an arrangement of parts that will now be described in detail, and for this purpose reference will be had to the accompanying drawing in which the invention has been illustrated in its preferred form, and in which:

Figure 1 is a top plan view of the wrench;

Figure 2 is a side elevation looking in the direction of arrow 2, in Figure 1;

Figure 3 is a transverse section taken on line 3—3, Figure 1;

Figure 4 is a side elevation similar to that shown in Figure 2, but showing a slightly modified form;

Figure 5 is a fragmentary plan view looking in the direction of arrow 5, in Figure 4; and

Figure 6 is a cross section taken on line 6—6, Figure 5.

The wrench consists of two substantially identical sides which have been designated by reference numeral 4. In the embodiment shown in Figures 1 to 3, these two sides are identical with the exception that one is a right and the other is a left. That part which extends the distance indicated by *h* comprises the handle and the other portion the jaw portion of the wrench.

It will be observed that the parts 4 have a reversely extending portion 5, whose inner edge is serrated as indicated at 6 and makes an angle *w* with the opposite side of the handle. The reversely bent or hook portions 5 are preferably connected with the other part of the sides by a curved portion which has been designated by reference numeral 7. The parts designated by reference numeral 5 are offset towards each other in the manner shown in Figure 2 and are con-

nected with each other by means of rivets 8. A spacer 9 is positioned between the outer ends of the handle and are held in position by means of a rivet 10. Pivoted at 11 is an auxiliary handle 12 that is provided on its inner surface with serrations 13. A slot 14 extends transversely across the auxiliary handle 12 and a rivet 15 extends through the handles and through the slot 14 and forms a limit stop which prevents the handle from being rotated about its pivot 11 to a greater extent than necessary for proper operation. The auxiliary handle 12, which also functions as a clamping jaw member, serves to grip a nut or a bolt and to urge it against the serrations 6 on the rearwardly extending jaws 5. By means of the auxiliary handle the nuts can be held from dropping and any round member can be urged against the teeth with considerable force, thereby assuring a firm gripping action.

In Figures 4, 5 and 6, a slightly modified form of construction has been shown. In this embodiment, the sides 4 are identical and do not have the inwardly offset portions shown in Figures 1 and 2. Instead of offsetting the ends they are separated by a piece of steel which has been designated by reference numeral 16. The steel insert is held in place by means of rivets 8 and the inner edge of this steel insert projects inwardly beyond the parts 5 and is provided with teeth. By this construction the handles 4 can be made of a soft steel, if desired, as the hard steel insert 16 only needs to be serrated. The advantage of this construction is that the two handle members are identical and can therefore be manufactured by a single die; whereas with the right and left construction shown in Figures 1 and 2, two dies are necessary. The auxiliary handle or clamping member 12 does not necessarily have to have serrations corresponding to those indicated by reference numeral 13 as its primary function is to urge the bolt or nut or pipe against the serrations on the reversely extending jaw.

Attention is called to the great simplicity of this device and particularly to the use of the auxiliary handle or jaw which greatly improves the operation over what it would be in case this element were omitted.

The pivot point 11 may be varied in position from that shown in the drawing, depending on the exact shape of the auxiliary clamping jaw or handle, but for the shape shown in the drawing, the position of pivot 11 is substantially correct.

From the above description it will be seen that this wrench is of an exceedingly simple construction; that the parts can be cut from suitable

stock by means of dies and that only a small amount of labor will be necessary for the assembling. The wrench thus formed can be used in connection with nuts and bolts of many different sizes and by increasing the length of slot 15, it is possible to bring the serrated edge 13 very close to the serrated edge 6 which may be desirable in some instances.

Having described the invention what is claimed as new is:

1. A wrench having a handle one end of which is rearwardly bent so as to form a hook whose sides form an acute angle, the rearwardly extending jaw having its inner edge serrated and a relatively straight auxiliary clamping jaw pivoted at one end to the wrench handle adjacent the reverse bend, the inner edges of the auxiliary jaw opposite the serrated edge, being movable into the angular space for clamping and holding a nut or the like, the free end of the auxiliary clamping jaw forming a lever and projecting beyond the outer edge of the handle whereby a force tending to rotate a nut will urge the auxiliary jaw into clamping position.
2. A wrench of the type specified comprising a combined handle and jaw formed from two identical pieces, each piece comprising a handle portion and a jaw portion formed by a rearwardly

- extending angularly related part, a spacer between the extreme ends of the handle, a steel spacer between the reversely extending jaws, the inner edge of the steel spacer having serrations that extend beyond the corresponding edges of the jaws, means for securing the handles and jaws to the spacers, and an auxiliary clamping jaw positioned between the handles and pivotally connected with the latter at a point near the reverse bend, the free end of the auxiliary clamping jaw extending beyond the sides of the handles, whereby any force applied to the wrench tending to turn a nut will urge the clamping jaw into engagement therewith.
- 10 3. A wrench having a handle one end of which is rearwardly bent so as to form a hook whose sides form an acute angle, and a relatively straight auxiliary clamping jaw pivoted at one end to the wrench handle adjacent the reverse bend, the inner edge of the auxiliary jaw, opposite the rearwardly bent end of the handle being notched and movable into the angular space for clamping and holding a nut or the like, the free end of the auxiliary clamping jaw forming a lever and projecting beyond the outer edge of the handle whereby a force tending to rotate a nut will urge the auxiliary jaw into clamping position.
